METHOD AND APPARATUS FOR FORMING
AND TRIMMING DIE CASTINGS

Louis H. Morin, Bronx, and Otto Gries, New Rochelle, N. Y.; said Gries assignor of his one-half to Crown Fastener Corporation, Warren, R. I., a corporation of Delaware

Application April 24, 1946, Serial No. 664,586

6 Claims. (Cl. 18—1)

1

This invention deals with the formation and trimming of die castings. More particularly, the invention comprises means for first forming a die casting at a casting station, the casting being what is termed a "Get," and consists of the cast article, including the gate, runner or get guide, and other parts of the complete unit casting formed. Further the invention comprises the gravity feeding of the get to a trimming station, at which station the get is trimmed and the finished trimmed casting and remainder of the get are separately discharged. Still more particularly, the invention deals with the method of forming and trimming gets, as more clearly hereinafter described and claimed. The novel features of the invention will be best understood from the following description when taken together with the accompanying drawings, in which certain embodiments of the invention are disclosed, and in which the separate parts are designated by suitable reference characters in each of the views, and in which:

Fig. 1 is a diagrammatic perspective view showing parts of a die casting machine and illustrating the method of forming and trimming die castings or gets.

Fig. 2 is a sectional detailed view of the upper portion of the apparatus, as seen in Fig. 1, showing parts preparatory to the injection of casting material into the dies in forming a casting.

Fig. 3 is a plan and sectional view of part of the construction shown in Fig. 1, illustrating the movable upper portion of the guide channels.

Fig. 4 is a sectional view through the trimming tools employed, and showing a casting or get supported between said tools.

Fig. 5 is a perspective view of a modified form of get wherein two substantially similar articles are simultaneously formed as part thereof; and

Fig. 6 is a view similar to Fig. 5, showing another modification.

In formation of die castings, it has been the common practice to form a casting at a casting station and then to mechanically and positively feed or deliver the casting to a trimming station. In this method of procedure, considerable time was occupied, in the cycle, in transferring the casting from the casting station to the trimming station, during which period, a next successive casting could not be formed. The result of this procedure has materially slowed down production, particularly from the standpoint that it is not practical or desirable to speed up operation of the machine in such manner as to perform

necessary functions and operations to acquire the desired higher production.

With our present apparatus and method, machine operation can be performed at a rate of speed which is considered practical, and as the casting operation, namely, injection of casting material into the die cavity is accomplished in a very short period of time in a cycle of operation, this formation of the casting can then be performed speedily and while one casting is being formed, the previously formed casting is trimmed and ejected from the machine. In other words, the machine can be operated just as fast as it takes to form a casting, and then gravity deliver the casting, or what we term a "get," to the trimming station, it being apparent that the casting at the trimming station is trimmed when the next successive casting is formed, the trimming tools being moved into operating position simultaneously in the operation of closing the dies.

With our improved method, an increased production of several hundred percent is possible without any strain or tax upon the machine or apparatus.

25 In Fig. 1 is shown diagrammatically, one adaptation of carrying this method into effect, and in this figure, 10—10' represent a pair of similar dies movable toward and from each other in any suitable manner. Each die has on its face a cavity or impression and as the face of the die 10 only is shown, reference characters will be applied thereto. The cavity impression comprises a product forming part 11, a sled or guide forming part 12, a recess part 13, in which is formed 30 a cast body for engaging a holding member, as later described, and a gate part 14, which opens directly into the part 12, the part 12 having the branches 15 and 16 leading to the parts 11 and 13 respectively. The various parts of the cavity or impression of the die forms a resulting cast member or unit which I generally term a "get" 35 17. The get consists of a ring like product 18, an elongated sled 19, having rounded ends 20—21, and a thimble-shaped portion 22 which is formed 40 about the rod or holding member 23. The gate portions of the get 17 are shown at 24, 25 and 26. 45

The holding rod 23, which also acts as a stripper removing the cast get 17 from the dies 10—10' in the separation thereof, has slidably mounted thereon a stripper sleeve 27 actuated through a clevis lever or similar operating member 28. The sleeve 27 normally seats upon the upper surfaces of the dies to close the cavity part 13 and then is later moved downwardly on the rod 23 in stripping the get 17 from the rod for delivery into

the upper movable portion 29 of the guide channel 30.

The guide channel 30, including the portion 29, is adapted to deliver or feed by gravity the casting or get 17 from the casting station between the dies, to a position between forming tools 31 and 32, at a trimming station, downward movement of the get in the channels being checked by a stop rod 33 adapted to maintain proper alignment of the get 17 between the trimming tools 31 and 32. The channel 30 comprises a pair of plates spaced apart and fashioned to form a large recess or channel portion 34 bordered at the outer edge of the guide 30 in unturned flanges 35, forming a narrow passage or channel 36 through which the parts 25 and 26 are free to pass. The enlarged channel portion 34 is adapted to receive the sled 19 freely but snugly so that the enlarged rounded ends 20 and 21 will bear upon the flanges 35 and shoulder portions 37 in maintaining proper position and alignment of the casting 18 between the trimming tools 31 and 32, as later described. Extending rearwardly from the large channel 34 is a narrow channel 38 adapted to receive the gate portion 24.

The movable upper part 29 of the channel 30 has two plate portions 39 and 40, collectively having inner channel surfaces conforming substantially with the channels 34, 36 and 38. The plates 39 and 40 are pivoted or swingably mounted on a rod 41 supported in a suitable bearing block 42, as shown in Figs. 1 and 3 of the drawing. Centrally of the bearing block is a spacing member 43 upon which a cam surface 44 on the plate 40 is adapted to operate in swinging the plate members 39 and 40 outwardly so as to separate said plate members against the action of a spring 45, note Fig. 3, seating in a recess, as at 46, in the bearing block 42, or one end thereof.

The purpose of this construction is to spread the members 39 and 40 to facilitate cleaning the same or the inner channel surfaces thereof, or to free a die casting or get which may, for any reason, be jammed or held therein. The members 39 and 40 have fingerpieces 39' and 40' to facilitate individual or collective swinging movement thereof. The members adjacent the channelled portions thereof are spaced apart to form a large opening 47 adapted to allow the parts 18 and 22 of the casting to pass freely therethrough.

The block 42 has an inner plate portion 48 adjustably supported in a bracket part 49 on the machine for alining the movable chute part 29 with the casting, the bracket part 49 supporting the chute 30, the plate 48 being retained in the bracket by a clamp plate or strip 50. It will be noted that the upper portion of the chute 30 is forwardly offset, as indicated at 51, particularly when the forming tools 31 and 32 are disposed forwardly with respect to the position of the dies 10-10' in the machine. In this connection it will be understood that the channel 30 may be shaped to direct the get to any desired trimming station or other station in the machine, gravity being utilized to deliver the get from one station to the other, thus dispensing with any type and kind of feed mechanism. In this respect the machine is materially simplified from an operative standpoint.

In Fig. 4 of the drawing is shown a diagrammatic section through the trimming tools 31 and 32, the tool 31 comprises a tubular die portion 52 for trimming the outer peripheral surface of

the ring type casting 18 to free it of any fins or flare of metal. Within the tubular trimming tool 52 is a core trimming tool 53 for trimming the bore of the ring casting 18 in the same manner. Slidably mounted on the core tool 53 within the tool 52, is a flanged sleeve 54 normally held in extended position by a spring 55, the flange 56 of the sleeve 54 seating upon the inner surface of the tool 52, as clearly seen in Fig. 4. The trimming tool 32 is in the form of a punch having a tubular end portion 57 adapted to slide over the tool 53 with the end of the punch engaging the casting 18 and pressing the same over the tool 53, forcing the sleeve 54 inwardly in the operation. As the tools 31 and 32 are brought together upon the casting 18, the casting is trimmed from the gate part 25 and the inner and outer periphery of the casting trimmed simultaneously. Upon separation of the tools 31 and 32, the sleeve 54 operates to eject or discharge the trimmed casting 18 from the tool 53 to discharge it into a suitable receptacle. During the above operation, and after the casting 18 has been trimmed from the remainder of the get, the remainder of the get is permitted to pass downwardly through the chute 30, the stop pin or member 33 having been withdrawn for this purpose. The remainder of the get may be collected in another receptacle so that these parts may be again returned to the melting pot of the machine for re-melting in forming other castings, thus affecting substantially no waste.

In Fig. 1 of the drawing, and also in Fig. 2, diagrammatically shown at 58, is the discharge end of a nozzle from which heated casting material from a suitable source of supply is pressure injected into the die cavities when the dies are in closed position.

As stated above, the upper movable portion 29 of the guide channel 30, or the plate members 39 and 40 thereof have the channel portions similar to the channel 30, and for purposes of description, particularly considering Fig. 3 of the drawing, reference characters 34', 36' and 38' are applied to designate like portions of the channels.

The trimming tool 31 is what is generally referred to as a compound trimming unit for trimming internal and external surfaces of the casting, and in practice, this unit first moves in the direction of the casting 18, after which the tool 32 or punch moves toward the casting, producing the trimming operation, as aforesaid.

In Figs. 1 to 4 inclusive, the invention has been shown as applied to the formation of a ring type single casting 18. Further in Figs. 5 and 6, I have shown other types of castings which can be formed in order to illustrate another one of the many adaptations and uses of the invention. For example, in Fig. 5 of the drawing, 59 and 60 represent two substantially similar castings in the form of pocketbook knobs which are united in the gate part 61, the latter joining the sled part 62 having the primary gate part 63. Extending from the sled part 62 is another gate part 64 which extends to a part 65 adapted to be formed around a rod or other holder, similar to the holder 23. However, instead of forming a cylindrical portion, as at 22, the part 65 comprises a substantially U-shaped body of the general form illustrated in Fig. 5. Here it may be pointed out that this body may be shaped to form an independent casting, in which event, the trimming tools employed would also trim such part from the remainder of the resulting get which is generally identified as 66 in Fig. 5 of the drawing. The

trimming tools employed will also trim each casting 59 and 60 from the gate portion 61, as well as trim the castings 59 and 60 of peripheral fins or flared metal, similar to trimming the inner and outer diameters of the casting 18.

In Fig. 6, the resulting get 66' differs from the get 66, substantially in that the sled part 62' comprises an end portion 67 substantially similar in cross section to the sled 62 of Fig. 5, the remainder of the sled being cut-out or recessed and shaped to form two pairs of guide pin portions 68 and 69 which are utilized to guide the sled in its passage through channels of a slide in guiding the get 66' from a casting to a trimming station.

In Fig. 6, 59' represents one casting, 60' another casting, both similar to the castings of Fig. 5; 61', 63' and 64' show the gate portions. Also in Fig. 6, the part 65' differs from the part 65 in being more or less cylindrical in form and modified with respect to the part 22 in having a reduced lower end portion 70. Here again the part 65' may comprise a secondary casting being formed simultaneously and as a unit part of the single get.

In connection with the formation of secondary castings, it will be apparent that within certain limits, secondary castings may be formed by shaping the holding member, such for example, as the member 23 to suit the resulting casting to be formed, so long as the secondary casting is free for removal from the holding member in the gravity feed of the casting or the complete get from the casting station to the trimming station. In this connection, it will also be apparent that instead of forming two substantially similar parts or castings, as 59—60, 59'—60', two distinct castings could be formed and simultaneously trimmed and removed from the remainder of the get at the trimming station.

Considering the two parts, such for example, as 18—22 and the parts 59, 60 and 65, 59', 60' and 65', it will further be apparent from a consideration of Fig. 1 of the drawing that as the primary casting, such for example, as 18 and the pairs of castings, as shown in Fig. 5 can be trimmed at one station and as the remainder of the get with the other part 22, 65 and 65' thereon is still in the slide, the slide may direct the remainder of the get to a secondary trimming station where the secondary casting may be trimmed or otherwise formed. This latter procedure would be desirable from a standpoint of simplifying the trimming tools employed.

Die castings may be formed from any type or kind of metallic or plastic castings, and particularly those using the injection molding principle where relatively high speed of production can be obtained. In accordance with my improved method, trimming operations are performed upon a casting while a next successive casting is being formed. It will thus appear from the standpoint of delivering the casting from the casting station to the trimming station and trimming the casting, there is no loss of time in actual production of castings. In other words, the machine can operate at a production basis consistent with the ability of a casting machine to produce successive individual castings. The gravity feed employed provides a quick delivery of the casting to the trimming station.

It will be noted from a consideration of Figs. 1 and 4 of the drawing that the trimming tool 52 is relieved, as seen at 52' to clear the remainder of the get, and particularly the part 22 thereon,

as the tools are brought into engagement with each other to trim the product 18.

Having fully described our invention, what we claim as new and desire to secure by Letters Patent is:

1. In apparatus for forming and trimming die castings, means at a casting station for forming a die cast body comprising a casting part, a body guide part and a body core engaging part, all of said parts of the body being integrally united, a trimming station comprising relatively movable trimming tools, said trimming station being disposed below and in spaced relation to the casting station, a chute for guiding a body between said stations, means for freeing a body formed at the casting station from said core when the dies are separated to deliver the guide part of the body to said chute in gravity feed and guide of the body to the trimming station, means at the trimming station for checking movement of the body in said chute and to align the casting part between the tools at the trimming station, means in said chute and on the guide part of the body for further aligning the body at the trimming station, said chute including an upper section comprising a pair of relatively movable chute plates, and means for pivotally mounting said plates to move toward and from the remainder of the chute.

2. The method of forming die cast bodies by means of a pair of relatively movable dies at a casting station and delivering them to a trimming station disposed below and in spaced relation to the casting station, which comprises forming on a core at the casting station a cast body comprising a product part, a core-engaging part and a guide part, freeing the body by opening the dies while maintaining the core stationary, then with the core still stationary stripping the body therefrom while the dies are open and out of contact with the body, dropping the body by gravity and without interrupting its fall to the trimming station, said guide part of the body serving to hold the body in a predetermined position during said fall, checking the fall of the body at the trimming station, supporting the body in said predetermined position at the trimming station, and then trimming the body by separating the product part from the core-engaging and guide parts.

3. In a die casting machine comprising a casting station and a trimming station arranged below and in spaced relation to the casting station, means at the casting station for producing a die cast body comprising a product part and a guide part, an elongated, normally open, vertical channel disposed between said stations and having means for engaging the guide part of said body, said channel comprising a pair of spaced walls the upper portions of which are movable relatively to each other, means for moving said upper portions to adjust the same relatively to each other, means at the casting station for discharging said body into said channel for free falling movement therethrough to the trimming station, the product part of the body extending outwardly of said walls during said free falling movement, means at the trimming station for checking the fall of said body and for supporting it in a trimming position, and means for removing the product part from the remainder of the body.

4. In a die casting machine comprising a casting station and a trimming station arranged below and in spaced relation to the casting station, means at the casting station including a pair of relatively movable dies and a core for producing

a die cast body comprising a product part, a guide part, and a core-engaging part, an elongated, open, vertical channel disposed between said stations and having means for engaging the guide part of said body, means at the casting station movable relatively to the core for stripping said body from the core and discharging the same into said channel for free falling movement therethrough to the trimming station, said channel having a side opening through which the product part of the body extends during its free fall therein, means at the trimming station for checking the fall of said body and for supporting it in a trimming position, and means for trimming the body.

5. In a die casting machine comprising a casting station and a trimming station arranged below and in spaced relation to the casting station, means at the casting station for producing a die cast body comprising a product part and a guide part, an elongated, open, vertical channel disposed between said stations and extending towards a storage station, said channel having means for engaging the guide part of said body, means at the casting station for discharging said body into said channel for free falling movement therethrough to the trimming station, movable means at the trimming station for checking the fall of said body and for supporting it in a trimming position, means for trimming the body,

means for withdrawing said movable means to permit the body comprising said guide part to fall freely through said channel to said storage station.

6. In a die casting machine comprising a casting station and a tool station arranged below and in spaced relation to the casting station, means at the casting station including a pair of relatively movable dies for producing a die cast body, an elongated vertical channel disposed between said stations, means at the casting station independent of the dies for discharging said body into said channel for free falling movement therethrough to the tool station, means at the tool station movable into and out of said channel for checking the fall of said body and for supporting it therein, and tool means at the tool station for engaging said body.
